UNITED STATES PATENT OFFICE.

MATTHEW VIERENGEL, OF BROOKLYN, NEW YORK.

CLOSURE-FLAP FOR ENVELOPS.

1,112,178.

Specification of Letters Patent. Patented Sept. 29, 1914.

Application filed June 20, 1913. Serial No. 774,867.

To all whom it may concern:

Be it known that I, MATTHEW VIERENGEL, a citizen of the United States, and a resident of Brooklyn, in the county of Kings and State of New York, have invented certain new and useful Improvements in Closure-Flaps for Envelops, of which the following is a full and clear specification.

This invention relates to envelops of the type generally known as metal flap or metal strap envelops.

The primary object of this invention is to provide improved means for securing a flexible strip to the envelop, it being customary in devices of this character to weave said strip into the edge of a flap, said flap being adapted to be folded over across the mouth of the envelop, after which the ends of the metal strip are bent around the edges of the body of said envelop to retain the flap in sealing position.

One of the objects of the present invention is to provide an improved construction for envelops of this character according to which there will be less waste of material, and according to which those portions of the material which are usually thrown away can be utilized to produce useful and beneficial results in the manner to be hereinafter explained.

Figure 1 is a rear elevation of an envelop constructed in accordance with the principles of my invention, one of the securing flaps being unattached to more clearly illustrate the construction; Fig. 2 is a top plan view of the envelop completed, and Fig. 3 is a fragmentary plan view illustrating the method of cutting the flaps, together with the metal straps secured thereto.

In the construction of envelops of the same general character as that disclosed in the following description, the form and methods of constructing dies and other parts co-operating therewith, as well as the arrangement of machine parts on envelop machines, make it desirable to construct the body of the envelop separately from the flap which carries the flexible strip or strap, the material of the flap being usually wrapped about the strap or strip. When finished, the envelop is therefore provided with a flexible strap at the top with laterally projecting wings, the flap being usually pasted to the

rear face of the body portion of the envelop around and within the edges of the flap. In consequence, when the envelop is opened the flexible tension in the strap at the top, tends to retain the flap in a plane while the body portion of the envelop is deformed, the result being that the flap is commonly separated along its lateral edges from the body portion of the envelop, and thus does not serve its function as fully as it should.

In the envelop constructed according to my own invention, the flaps are cut from a continuous strip as indicated in Fig. 3, simultaneously with the operation which imparts the desired form to said flaps. Thus it will be seen that comparatively little material is wasted, the waste corresponding to the recesses 6 between the wings 7 and the attaching lobes 8. When the flap with the flexible strap is secured to the body 9 of the envelop, the lobes 8 are folded around to the front face of the envelop and pasted thereto, as indicated in Figs. 1 and 2. According to the well-known method of construction of these portions of the envelop a rectangular piece of material is cut out and thrown away. Another operation severs the wrapped strap. Not only therefore are two operations required, but portions of the material are thrown away which are utilized by me in more securely attaching a flexible strap to the envelop. Furthermore, by means of my construction, the flap which holds the flexible strap to the envelop, need not be made so broad and hence enables a considerable saving in material. As shown in Fig. 1, the recesses 6 between the flaps 7 and lobes 8 are rounded at 12 to distribute the stress which tends to tear the paper at the points 12.

What I claim is:

A flap-forming attachment for flapless envelops comprising a sheet of material of greater width than the envelop to which it is to be attached, and having oppositely disposed recesses, the innermost edges of which are spaced apart a distance substantially equal to the width of said envelop, said recesses dividing the sheet into portions constituting respectively an attaching portion and a flap-forming portion, said recesses providing the attaching portion with lobes adapted to be folded around the lateral edges of the flapless envelop to be sealed to

the outside wall of said envelop opposite to the face on which the attaching portion is to be imposed, and said flap-forming portion having a flexible metal strip rolled therein to be folded about the lateral edges of said envelop when the flap portion is in envelop closing position, the edge of said strip being spaced from said attaching portion by substantially the width of said recesses.

MATTHEW VIERENGEL.
